UNITED STATES PATENT OFFICE.

SIDNEY C. VINCENT, OF BALTIMORE, MARYLAND, ASSIGNEE TO THE ELECTRO-CLOCK COMPANY, A CORPORATION OF DELAWARE.

ELECTRIC CLOCK.

1,032,987.

Specification of Letters Patent.

Patented Apr. 9, 1912.

Application filed June 16, 1911. Serial No. 683,560.

To all whom it may concern:

Be it known that I, SIDNEY C. VINCENT, of Baltimore, Maryland, have invented certain improvements in Electric Clocks, of which the following is a specification.

This invention relates to certain improvements in the invention set forth and described in Letters Patent, No. 901,050 granted to Charles H. White, on the 13th day of October 1908, for an electric clock, and to which patent, reference should be made.

The present invention is for the purpose of simplifying the construction, and increasing the general efficiency of the clock, as will hereinafter fully appear.

In the further description of the said invention which follows reference is made to the accompanying drawings, forming a part hereof and in which—

Figure 1 is an exterior front view of such parts of the clock movement as are involved in the present invention. Fig. 2 is a side view of Fig. 1, looking in the direction indicated by the arrow in that figure. Figs. 3, 4 and 5 are details of the invention, hereinafter described.

Referring now to the drawings, 1, 1 are the front and rear plates of the clock movement, and 2 is the minute arbor to which is fastened the first gear wheel 3 of the train of gearing comprised in the movement. The wheel 3 meshes with the pinion 4 on the arbor 5, and the said arbor also carries the spur wheel 7 which drives the pinion 10 on the escapement arbor 11. The escapement wheel is denoted by 13. All the parts of the clock movement thus far described are common in clocks.

14 is a rocker (see particularly Figs. 3 and 4) constructed of sheet metal and hung loosely on the minute arbor 2. The central portion or crown of the rocker is elevated above the arbor and made flat, and its ends 46 are bent downward to form the parallel curved plates, *a* and *b*, to the extremities of which are fastened by means of screws *c*, the armature 15 hereinafter more particularly referred to.

50 The curved arm *a* of the rocker 14 has a downwardly extending straight branch arm *d* to which a spring-held pawl 17 is pivoted; and from the crown extends the twisted lever *e* upon which the actuating weight 19 is fastened by a set screw.

20 is a ratchet wheel which is loose on the minute arbor 2, with its teeth in engagement with the spring-held pawl 17 on the branch arm *d* of the rocker 14. In order that the ratchet wheel which as before stated is loose on the minute arbor, and is rotated by means of the weight on the twisted lever *e* as the same descends by gravity, may communicate its rotation to the gear wheel 3 which is fast on the minute arbor, one of the arms *f* of 60 the gear wheel is provided with a short laterally extending pin *g* shown in dotted lines in Fig. 1, which is in the path of one of the similar arms *h* of the ratchet wheel. A backward movement of the ratchet wheel is 70 prevented by means of the pawl 18.

21 is a subsidiary rocker (see Figs. 3 and 4) which like the main rocker 14 is loose on the minute arbor 2. It is situated between the arms *a* and *b* of the main rocker 75 and a part of the edge of its side *k* serves as a cam *i*. The cam *i* is at all times in contact with a pin *j* which projects from a lever 22 fastened to the arbor 23 the ends of which are pivoted in the plates 1. 80

The pin *j* of the lever 22 is yieldingly held in contact with the cam *i* by means of the coiled spring 25, and its free end is adapted to make electrical contact with the insulated spring plate 27 which with the said lever, 85 is in an electric circuit of which for the sake of simplicity in construction, the said spring forms a part.

By reference to Figs. 1, 3 and 4 it will be seen that there is a space between the upper 90 side of the subsidiary rocker 21, and the under side of the main rocker 14, and that the arms of the latter are provided with the screws *m* the ends of which do not touch the subsidiary rocker when the crowns of 95 the two rockers are in practically parallel lines, and in consequence the main rocker when moved by the upward or downward motion of the weighted lever *e* does not communicate any movement to the subsidiary 100 rocker until one or other of the screws *m* strikes its upper surface. By this construction there is established considerable loose motion between the two rockers which is availed of to extend the time during which 105 the lever 22 is in contact with the spring plate 27, and to a less extent, the time during which it is detached from that device, in the operation of the clock.

The distance of the full or curved por- 110

tion of the cam 4 from the arbor 2 is such that when it is in contact with the pin 5 projecting from the lever 22 the said lever is held from the contact plate 27 and the electric circuit is thereby broken. When the flat edge of the cam 4 is in contact with the pin 5 as shown best in Fig. 4, the lever 22 will ascend sufficiently to bring its end into contact with the spring plate 27, and close the electric circuit.

In Figs. 1 and 2 an ordinary maintaining spring 6 is shown as connecting the gear wheel 8 with the ratchet wheel 20.

By combining the main and supplemental 15 rockers 14 and 21, respectively, and their connection with the devices having substantially the same functions, shown in the said Letters Patent, it will be seen that the present clock is simplified in construction, and 20 the entire apparatus more easily and cheaply manufactured, and less liable to disarrangement. In the manufacture of clocks the employment of casings as elements of the mechanism should be avoided and in the 25 present invention, sheet metal has been used wherever possible, so as to reduce the momentum of the moving parts. It will also be seen that in the present invention the number of parts employed in the construction 30 of the clock has also been reduced which further simplifies and cheapens the apparatus.

The adjacent faces of the armature 16 before referred to, and the cores 23 of the 35 electric magnets 30, are curved as in the patented invention.

The operation of the clock is substantially the same as that set out in the Letters Patent, and may be briefly described as follows:—In Figs. 1 and 2 of the drawing the electric circuit formed by the lever 22, the wires 4 of the magnets 30, and the spring plate 27, is shown as closed, and in consequence the magnets are energized, and the 45 armature 16 is thereby drawn toward the cores of the magnets, and the weighted lever 5 which has a movement in common with the armature but in a reverse direction is carried upward. When the weighted lever 50 has reached a predetermined height, the full or curved portion of the cam 4 comes into contact with the pin 5 and the lever 22 is forced downward which breaks the electric circuit at the spring contact plate 27. The 55 weighted lever 5 then begins to fall and cause the rotation of the ratchet wheel through the agency of the pawl 17, and the train of gearing receiving its motion therefrom. This operation of the clock continues until 60 the weighted lever has reached its lowest

position when inactive or flat portion of the cam 4 engages the pin 5 and the electric circuit is again closed which causes the upward motion of the weighted arm, and the operation as above described is repeated.

I claim as my invention,—

1. In an electric clock movement, the minute arbor thereof provided with a loose ratchet wheel, and an adjacent tight spur gear wheel which constitutes the first wheel of the train of gearing, the said spur wheel having a horizontally projecting pin situated between its center and periphery, adapted to engage a portion of the ratchet wheel by which the spur wheel is driven, combined with a rocker hung loosely on the arbor and which comprises the following elements, a crown situated above the arbor depending sides which support an armature, a lever adapted to carry an actuating weight, and an arm arranged to sustain a spring held pawl to drive the ratchet wheel, the said elements of the rocker being constructed as in one piece from sheet metal, substantially as specified.

2. In an electric clock movement, the minute arbor thereof provided with a loose ratchet wheel and an adjacent spur gear wheel which is tight on the arbor and constitutes the first wheel of the train of gearing, the said wheel having a horizontally projecting pin situated between the center of the wheel and its periphery, adapted to engage a portion of the ratchet wheel by which the spur wheel is driven, a rocker which is hung loosely on the arbor which comprises as elements thereof, a crown situated above the arbor, depending sides which support an armature, a lever adapted to carry an actuating weight and an arm having a spring held pawl to rotate the ratchet wheel, the said elements being constructed as of one piece from sheet metal, combined with a subsidiary rocker hung loosely on the arbor between the depending plates of the main rocker a cam formed as a part of the subsidiary rocker, a swinging spring held lever an insulated spring plate with which the end of the spring held lever is adapted to come in contact and close an electric circuit, a pin projecting from the said lever and in contact with the face of the cam, and screws which pass through the crown of the main rocker adapted to impart its motion to the subsidiary rocker, substantially as specified.

SIDNEY C. VINCENT.
